(57) **CLAIM**

We claim the ornamental design for an electronic device with graphical user interface, as shown and described.

DESCRIPTION

FIG. 1 is a front perspective view of a first embodiment of an electronic device with graphical user interface showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the graphical user interface in FIG. 2, shown separately from the electronic device;

FIG. 9 is a front perspective view of a second embodiment of an electronic device with graphical user interface showing our new design;

FIG. 10 is a front view thereof;

FIG. 11 is a rear view thereof;

FIG. 12 is a left-side view thereof;

FIG. 13 is a right-side view thereof;

FIG. 14 is a top view thereof;

FIG. 15 is a bottom view thereof; and,

FIG. 16 is an enlarged view of the graphical user interface in FIG. 10, shown separately from the electronic device.

The evenly-dashed broken lines in the figures depict portions of the electronic device which form no part of the claimed design.

The dot-dash broken lines in the figures represent a boundary of the claimed design and form no part thereof.
